4 Claims

This invention relates to particularly elegant and effective antacid tablets and, more particularly, to a chewable antacid tablet comprising a major proportion of water-insoluble antacid agent, a major proportion of mannitol and a minor proportion of urea.

Aqueous suspensions of antacids such as aluminum hydroxide, alone or in combination with other antacids such as magnesium hydroxide, are effective medication for the control of gastric hyperacidity and gastric ulcers. In the practical management of these conditions, however, the need exists for a dosage form which is more convenient and readily available to the patient during his routine, daily activities. Tablets have been used to meet this need but for maximum usefulness such tablets must be capable of being chewed and swallowed without water and if chewed, be free of objectionable characteristics and must also provide sufficient antacid activity.

It is commonly accepted that the human stomach contains about 50 ml. of 0.1 N hydrochloric acid after a meal. During the next two hours this will be supplemented by the secretion of about 240 ml. of 0.1 N hydrochloric acid. It is expected that patients secreting larger amounts of hydrochloric acid will be able to obtain relief by taking a sufficient number of doses of an antacid as measured by their own observed relief from discomfort. It is also recognized that an individual with a gastric ulcer will

tablets is such that they are too gritty as a practical matter to be conveniently chewed to any finer particle size.

The antacid activity of a given tablet can therefore be measured, when particle size is taken into account, by the procedure of E. Fuchs, Drug and Cosmetic Industry, 64, 692 (1949). As this method was used herein a reaction vessel was charged with 25 ml. of 0.1 N hydrochloric acid and 125 ml. of deionized water. The reaction vessel was equipped with thermometer and pH electrodes and maintained at 37° C. $\pm 1^\circ$ in a constant temperature bath. Intact tablets were placed in a U.S.P. disintegration apparatus and introduced directly into this reaction medium. The powdered tablets were first wet with ten drops of a 10% solution of a wetting agent ("Triton X-100") in five ml. of water and diluted with an additional 120 ml. of water. The 25 ml. of 0.1 N hydrochloric acid was then added immediately and agitation initiated simultaneously. The surfactant was found necessary to assure wetting since the hydrophobic nature of the components in many of the tablets prevented ready dispersion.

With the start of immersion or agitation, the pH was recorded immediately and at the end of the first, third, fifth and tenth minutes. At this point, and after each ten minutes reading thereafter, 1 ml. of 1.0 N hydrochloric acid was added. The procedure was followed until the reading was below pH 3 when the next increment of acid was due to be added. Triplicate runs were made, and the results averaged.

A tablet was not considered to provide satisfactory buffering activity unless the pH in this test was held within the range of pH 3.0–5.0 for at least eighty (80) minutes.

35 Ten antacid tablets of the composition listed below in

TABLE

Composition	Labeled dosage and instructions	Ave. Comb. active ingredients per tablet	Average tablet weight, grams
Calcium carbonate, glycine	1 or 2 tablets as needed, chew, melt in mouth or swallow whole.	.600	.651
Dried aluminum hydroxide gel (stabilized with hexitol), magnesium hydroxide.	2 to 4 tablets as necessary, chewed or swallowed whole.	.395	.690
Aluminum hydroxide, magnesium hydroxide.	2 to 4 tablets, chewed or swallowed.	.400	.473
Aluminum hydroxide with magnesium hydroxide.	1 or 2 tablets as required. May be chewed before swallowing.	.420	.925
Dried aluminum hydroxide gel.	Swallow 1 or 2 tablets.	.324	.529
Dried aluminum hydroxide gel, magnesium trisilicate, magnesium hydroxide. ¹	1 or 2 tablets chewed, sucked or taken with water as necessary.	.520	.987
Aluminum hydroxide-magnesium carbonate co-dried gel in a dextrose and milk solids base. ¹	1 or 2 tablets as required. Chewed or swallowed.	.375	1.634
Aluminum hydroxide, magnesium hydroxide ¹ .	1 or 2 tablets, may be chewed or swallowed with water.	.420	.928
Dried aluminum hydroxide gel ¹ .	1 or 2 tablets.	.324	.993
Magnesium trisilicate, dried aluminum hydroxide gel ¹ .	1 to 4 tablets as necessary, chewed, swallowed or allowed to disintegrate in the mouth.	.748	1.340

¹ Australian products.

obtain relief by adjusting the contents of his stomach to a pH of from 3 to 5. Any lesser pH will result in pain from the acid and any pH substantially greater than 5 will result in the highly undesirable phenomenon known as "acid rebound" as is observed, for example, when simple sodium bicarbonate is used as an antacid.

It is further recognized that any test of the antacid activity of the tablet must take into account the manner in which it disintegrates in the stomach and the size of the particles into which the tablet has been broken if it is chewed before it is swallowed. The U.S.P. XVI tablet disintegration test has been used extensively to simulate the conditions which prevail in the human stomach. Examination of commercially available antacid tablets after they have been chewed and expectorated shows that the majority of particles are no finer than sufficient to pass a 10-mesh screen; the nature of the material in these

60 the table were obtained from the open market in the U.S.A. or Australia and their duration of action in the effective range of pH 3.0–5.0 in minutes was measured.

To provide the proper analogy to conditions in the human body it was also necessary to take into account the particle size after disintegration of these tablets. This was done in two ways.

In the first method the tablet in the acid reaction cell was placed in a basket having a 10-mesh screen on the bottom which was raised and lowered as in the U.S.P. disintegration test. This simulated the conditions found when the tablet was swallowed without chewing.

65 In a second test the tablet was ground to pass a 10-mesh screen (simulating the size obtained when the tablet was chewed and then swallowed), placed in the acid of the reaction cell and mixed with a perforated disc which was raised and lowered as in the U.S.P. disintegration test.

It was found that, under these conditions simulating what actually occurs in the human body, such commercial tablets in general failed to provide anything approaching their theoretical buffering capacity. For example six of the ten whole tablets never raised the pH to the minimum satisfactory level of pH 3 and one of the ten whole tablets quickly raised the pH above the maximum acceptable level of pH 5 and kept it there for a considerable time.

When the tablets were ground to 10-mesh to duplicate the effect of chewing prior to swallowing, only one gave a duration of action greater than 65 minutes in the desired range of pH 3-5 and six of the tablets remained in the effective range for periods of less than 40 minutes with two of them not reaching that range at all and another going above pH 5 for all but 16 minutes. In addition, the three tablets which when 10-mesh remained in the effective range of pH for 65, 65 and 90 minutes respectively, were each evaluated as being much too gritty upon chewing. This would obviously militate against their continued use and chewing by the patient for the extended periods of time over which these tablets must be taken by patients with gastric ulcers. It was therefore apparent that the presently available antacid tablets as judged by the ten different products tested were far from being acceptable antacid agents.

Chewable tablets of other types of pharmaceutical agents, e.g. antibiotics, have been formulated using large amounts of mannitol in the tablet but this is not practical in the case of antacids such as aluminum hydroxide and the like because such tablets if of a reasonably small size are much too astringent and dry to chew without water, i.e. antacid agents of this type dry up the mouth to an unacceptable extent.

The use in ordinary antacid tablet formulation of agents such as aluminum hydroxide in finely divided form (e.g., greater than 200-mesh) is customary but fails to provide particles of such small size in the stomach when used. This undesirable effect may be due to the compression which must be applied to form the tablet or due to the other conventional manufacturing procedures used in preparing the tablets. Other common expedients do not serve to provide the proper particle size. Thus, use of wetting agents gives too bitter a taste. Admixture with simple water-soluble substances is not effective; thus, sodium chloride is too saline, sucrose is too sweet and lactose is not effective.

It was therefore the objective of the present invention to provide an antacid tablet, e.g., of the type containing aluminum hydroxide alone or in combination with similar antacids such as magnesium hydroxide, which would provide, as measured by the test described above, a duration of action in the effective range of pH 3-5 of at least 80 minutes and which would also have chewing properties of sufficient elegance to encourage and make possible long-term use, i.e., would give a feel in the mouth upon chewing which was not astringent, pasty, dry, chalky or slimy, which was neither too hard nor too soft when chewed and which was not gritty when chewed and which could be chewed and swallowed without water.

The objects of the present invention have been achieved by the provision, according to the present invention of a chewable antacid tablet comprising a major proportion of water-insoluble antacid agent, a major proportion of mannitol and a minor proportion of urea.

Preferred embodiments of the present invention are a chewable antacid tablet comprising by weight 35 to 60% of water-insoluble antacid agent selected from the group consisting of aluminum hydroxide, magnesium hydroxide, magnesium oxide, magnesium carbonate and magnesium trisilicate and mixtures thereof, at least about 25% and preferably about 25 to 50% of mannitol and about 4 to 10% urea; a chewable antacid tablet comprising by weight about 35 to 60% of water-insoluble antacid agent, said agent being a mixture consisting of more than one-half

aluminum hydroxide and less than one-half magnesium hydroxide, about 25 to 50% of mannitol and about 4 to 10% urea; a chewable antacid tablet comprising by weight about 50% of water-insoluble antacid agent, about 35% by weight of mannitol and about 7% by weight of urea.

The water-insoluble antacids used in the tablet of the present invention include the hydroxides, carbonates, trisilicates and oxides of aluminum, magnesium and calcium and other known neutralizing agents such as are disclosed above and in textbooks of pharmacy and medicine and, for example, in U.S. Patents 1,964,696; 2,446,981; 2,588,090; 2,641,604; 2,686,800; 2,797,978; 2,802,773; 2,907,781; 3,047,602 and 3,099,524 and mixtures thereof.

The term antacid agent as used herein includes both such individual compounds and mixtures thereof.

The tablets of the present invention contain, when desired, sweetening agents, flavors, tableting lubricants, fillers and the like and may also contain additional therapeutic agents such as antispasmodics (e.g., aminopentamide), antisecretory agents, tranquilizers (e.g., reserpine, meprobamate), antiflatulents (e.g., methylpolysiloxane), sedatives (e.g., phenobarbital), analgesics, local anesthetics or compatible combinations thereof.

Included within the present invention is the process of preparing a chewable antacid tablet which comprises first blending a major proportion of antacid agent and a major proportion of mannitol with a minor proportion of urea, next further reducing said mixture in particle size by mechanical means and finally forming said mixture into tablets.

The following example will serve to illustrate the present invention but the invention is not limited thereto and includes within its scope such variations in ingredients and proportions thereof as are well known to those skilled in this art.

¹ Finished tablet weight must be adjusted to include the water remaining in the granulation after drying.

MANUFACTURING INSTRUCTIONS FOR 1,000 TABLETS

55 (1) Prepare 266.0 grams of 5% (w./w.) starch paste by heating 13.30 grams of corn starch dispersed in 252.7 ml. of purified water, U.S.P., to boiling. Sufficient agitation should be used during this step to avoid scorching. Remove heat and maintain agitation until cooled to 25° C.

60 (2) Add sufficient purified water, U.S.P., to bring the weight up to 266.0 grams and mix to obtain a homogeneous paste.

65 (3) Combine the aluminum hydroxide, magnesium hydroxide, mannitol, urea, sodium Sucaryl and sodium saccharin (e.g., in a pony pan) and blend at slow speed for 15 minutes.

70 (4) Pass the blend through a milling machine to break up any lumps (e.g. through a Fitz mill at high speed with impact forward using a M00 screen).

75 (5) With agitation in the blender remaining at low speed, rapidly add all of the starch paste from step No. 1 and mix until a uniform dispersion is obtained. The mix appears dry at this point but usually contains enough

moisture to form the granulation. If necessary, additional water may be added to facilitate the formation of the strands of granulation described in the next step.

(6) Pass the mix through a granulator (e.g., a Stokes oscillator, with funnel removed using a No. 6 mesh stainless steel screen) and collect directly on drying trays. If strands of granulation are not being formed, additional water must be added to the mix.

(7) Spread the granulation evenly on the trays and dry (e.g., in a Stokes oven) at 38° C. until the moisture content is 4.5-5.5%.

(8) Mill using a combination of screen, speed and blade adjustment which will produce the greatest yield of 30- to 60-mesh granules.

(9) Separate the granules retained on a 60-mesh screen, add 5.48% magnesium stearate and hold.

(10) To the fines passing through a 60-mesh screen add 5.48% magnesium stearate and blend thoroughly.

(11) Slug at a weight of 0.470 gram using 1/2 inch, flat punches to a hardness of 5 to 7 kg. Reduce the slugs to 30- to 60-mesh granules and repeat the process until not more than 15% nor less than 10% of fines passing through a 60-mesh screen remain.

(12) Combine the lubricated granules from step No. 9 with the granules and fines from step No. 11. Add the flavors and blend thoroughly for 30 minutes.

(13) Tablet using 5/8 inch, flat, beveled edge punches to a hardness of 11 kg. or 1/2 inch square, concave punches to a hardness of 9 to 10 kg. (Strong-Cobb-Arner tester).

These tablets when chewed and expectorated were found to pass a 100-mesh screen. These tablets when ground to 100-mesh and tested as described above gave a duration of action in the effective pH range (3.0-5.0) of 81 minutes. The chewing properties of these tablets were evaluated as follows:

Flavor -----	Very good.
Mouth feel -----	Cooling.
Chewing characteristics -----	Very good.
Chewing hardness -----	Medium.
Not gritty.	

While in the foregoing specification various embodiments of this invention have been set forth and specific details thereof elaborated for the purpose of illustration, it will be apparent to those skilled in the art that this

invention is susceptible to other embodiments and that many of these details can be varied widely without departing from the basic concept and spirit of the invention.

We claim:

1. A chewable antacid tablet comprising by weight about 35-60% of water-insoluble antacid agent selected from the group consisting of aluminum hydroxide, magnesium hydroxide, magnesium oxide, magnesium carbonate and magnesium trisilicate and mixtures thereof, about 25-50% of mannitol and about 4-10% urea.

2. A chewable antacid tablet comprising by weight about one-half water-insoluble antacid agent selected from the group consisting of aluminum hydroxide, magnesium hydroxide, magnesium oxide, magnesium carbonate and magnesium trisilicate and mixtures thereof, about one-third mannitol and about one-tenth urea.

3. A chewable antacid tablet comprising by weight about 35 to 60% of water-insoluble antacid agent, said agent being a mixture consisting of more than one-half aluminum hydroxide and less than one-half magnesium hydroxide, about 25 to 50% of mannitol and about 4 to 10% urea.

4. A chewable antacid tablet comprising by weight about one-half water-insoluble antacid agent, said agent being a mixture consisting of more than one-half aluminum hydroxide and less than one-half magnesium hydroxide, about one-third mannitol and about one-tenth urea.
